UNITED STATES PATENT OFFICE.

ISAAC C. BRYANT, OF PHILADELPHIA, PENNSYLVANIA.

BRICKS AND DRAINAGE-PIPES.

Specification forming part of Letters Patent No. 42,926, dated May 31, 1864.

To all whom it may concern:

Be it known that I, I. C. BRYANT, of the city of Philadelphia and State of Pennsylvania, have invented new and useful Improvements in Machines for Making Bricks and Drainage or other Pipes; and I do hereby declare that the following is a full and exact description thereof, reference being had to the accompanying drawings, and to the letters of reference marked thereon, making a part of this specification.

The nature of my invention consists in the construction and arrangement of a revolving cylinder over a stationary horizontal screw; also, the combination of a roller and tempering-chamber; also, the end or mouth pieces to form the bricks or pipes; also, the elastic and lateral motion of the knife.

To enable others skilled in the art to make and use my invention, I will proceed to describe its operation and construction.

Figure 1 represents a sectional view of the screws; Fig. 2, an end view of the machine; Fig. 3, a side elevation of the machine; Fig. 4, a sectional view of the square mouth-piece that forms the bricks. Figs. 5 and 6 are sectional views of the mouth-piece that forms the pipes.

A represents the hopper in which the dampened clay is put.

B represents the roller that forces the clay into the mouth-pieces C, and against the tempering-teeth D, that are located on the outside of the mouth-pieces C, that taper from the outside case or tempering-chamber, F, toward the center of the stationary screw G. The front teeth, D, are not so long as the back ones, so as to correspond with the outside shape of the mouth-pieces C, that they may revolve near the concave of the outside case, F, and between each of the teeth H that are on the inside of the case F, for the purpose of effectually tempering the clay.

I is a head piece that is a bearing for the screw G, the revolving cylinder J, and the outside case, F. K is another bearing that supports the case, F, hopper A, and journal of the roller B. The stationary screw G is intended to be permanently fastened in the center of the machine, and extend the whole or any part of the length of the revolving cylinder J. This screw G is similar to a double auger, (but I do not wish to confine myself to

the use of a double or single auger,) but it should taper from where it meets the revolving screw L, that is on the inside of the revolving cylinder J. These flanges of the screw L may extend a part, one turn, or the whole length of the revolving cylinder J, and taper to correspond with the taper of the screw G, as I deem most effectual, so that the screw L may move in an opposite direction across the flanges of the screw G, and be operated either as a right or left hand screw, by making the permanent screw G a right-hand screw, the revolving one, L, will be a left-hand screw, or changing the stationary screw G to a left-hand screw, then the revolving screw L on the cylinder J will be a right-hand one, and thus I intend to work my machine to the right or left, as most convenient or effectual. The screw G is supported by a cross-bar, M, at the mouth of the cylinder when the screw is used the whole length.

N is an upright bearing for the revolving cylinder J, which has a flange, P, that works in a groove of the bearing.

Q is a grooved collar on the mouth of the cylinder J, which operates in the upright bearing R, so that the collar can be taken off when worn and replaced by a new one, as the mouth of the revolving cylinder J would wear the soonest, and this saves the expense of a new cylinder.

S is a dovetail into which a square mouth-piece, T, (for forming a brick or a round mouth-piece with a mandrel inside and inserted in the end of the screw G for forming drainage or other pipes) is inserted. Both mouth-pieces T will have a spring-guide, U, in front, which guides the knife V between its sides, as it descends to cut off the brick or the pipe the size or length required. The knife V revolves and operates on a pivot, and is regulated by a spring, W, in front of the pivot to make it spring to its place. It has a balance-handle, X, to give the knife its proper equilibrium when revolving, and two spiral springs, Y, on each side, that give it also an elastic lateral motion, so that in descending to cut off the clay as it is discharged from the mouth of the machine, the knife is relieved of stiffness and cannot be stopped or broken off. The knife revolves on a horizontal shaft, Z, working on an upright frame or bearing, a.

b is an apron in front of the machine, that

operates on an upright frame or bearings, *c c*, to receive and carry off the bricks or pipes *a* cut off at the mouth *U* of the machine.

d is the main driving-wheel, attached to a long horizontal shaft, *e*, underneath the machine, that drives the pinion *f*, that gears into the cog-wheel *g* of the revolving cylinder *J*, which drives the cog-wheel *h*, located on the shaft of the roller *B*, by which the roller *B* is operated. On the outer end of the shaft *e* is a band-wheel, *i*, that is geared by a belt to the pulley-wheel *j* on the shaft *Z*, that drives and revolves the knife *V*. The band-wheel *i* also gears into another friction or pulley wheel, *k*, that is geared by a belt to the shaft of the apron *b*, and operates the apron. Thus the machine is geared and operates, so that as the clay is put into the hopper *A* it is drawn by the roller *B* into the tempering-chamber inside of the case *F*, and completely tempered, then forced and carried along by the screw *L* on the inside of the revolving cylinder *J*, over the stationary screw *G* to the square mouth-piece *T*, where it is formed into a square brick, when bricks are to be made (or by using the round mouth-piece *T* when pipes are to be made) and cut off by the revolving knife *V*, the size of the brick required or the length of the pipe required, and from thence carried off by the apron *b*, all operating with regularity, precision, and great rapidity, thus manufacturing bricks or pipes by the same operation by simply changing the mouth-piece *T*.

What I claim as my invention, and desire to secure by Letters Patent, is—

1. The placing of a permanent screw, *G*,

with double or single thread, and a revolving cylinder or chamber, *J*, with a short or long screw, *L*, in it, with right or left hand screw in either the revolving chamber or permanent screw.

2. Giving to the revolving screw *L* and permanent screw *G* the tapering form.

3. The peculiar form of the tempering-teeth *D* and mouth-piece *C*, so as after tempering the clay they will force it close to and into the permanent screw *G* and revolving cylinder *J*.

4. The application of the two screws *G* and *L*, the inside one permanent and the outside one revolving in combination with the tempering-teeth *D*, with the case *F* around the tempering-teeth *D*, and forming the tempering-chamber, with roller *B* in an opening of the outside case, *F*, so as to force the clay against the mouth-piece *C* and into the screws *L*.

5. The combination of the knife *V* with a revolving handle and spiral or other springs, to give it a spring and elastic lateral motion, so as to cut off drainage or other pipe and bricks at right angles with the pipe or bricks, as described.

6. The mouth-piece *T*, with one or more openings in it, and a guide *U* on it for the purpose of guiding the knife for cutting off drainage or pipe and bricks, as described.

7. The combination of a round mouth-piece with a forming-mandrel inside of it, and so placed in the end of the screw as to form the inside of drainage or other pipe, as described.

ISAAC C. BRYANT.
